(57) **CLAIM**

The ornamental design for footwear, as shown and described.

DESCRIPTION

FIG. 1 is a top plan view of an embodiment of footwear according to the present subject matter;

FIG. 2 is a bottom plan view of the embodiment of footwear shown in FIG. 1 according to the present subject matter;

FIG. 3 is a left side plan view of the embodiment of footwear shown in FIG. 1 according to the present subject matter;

FIG. 4 is a right side view of the embodiment of footwear shown in FIG. 1 according to the present subject matter;

FIG. 5 is a rear view of the embodiment of footwear shown in FIG. 1 according to the present subject matter;

FIG. 6 is a front view of the embodiment of footwear shown in FIG. 1 according to the present subject matter; and,

FIG. 7 is a top perspective view of the embodiment of footwear shown in FIG. 1 according to the present subject matter.

The material shown in dashed lines in FIGS. 1 to 7 forms no part of the ornamental design.
